GEORGE WETTIG, OF NEW ALBANY, INDIANA, ASSIGNOR TO BEYNROTH & WETTIG, A COPARTNERSHIP.

DOOR-LATCH.

948,119.

Specification of Letters Patent. Patented Feb. 1, 1910.

Application filed October 2, 1907. Serial No. 395,582.

To all whom it may concern:

Be it known that I, GEORGE WETTIG, a citizen of the United States, residing at New Albany, in the county of Floyd and State 5 of Indiana, have invented a new and useful Door-Latch, of which the following is a specification.

This invention relates to improvements in latches for securing doors, drawers and the 10 like; and the objects of my improvement are, security against shaking or jarring open, to provide a latch which automatically takes up all lost motion between a door and the door-casing and consequently prevents 15 rattling, comparative inexpensiveness of manufacture, to provide a latch which may be used with some security as a lock, especially the saving of time and labor in fitting to the door, and, dispensing with the conventional strike or keeper. These objects I attain by means of the device illustrated in the accompanying drawing in which—

Figure 1 is a view showing the latch partly in longitudinal section and a door, to 25 which it is applied, in transverse section; Fig. 2, a view similar to Fig. 1, showing the latch in the open position; Fig. 3, a rear or inside view; Fig. 4, a face or outside view; Fig. 5, a perspective view of the latch as 30 assembled; Fig. 6, a plan view of the blank from which the casing is formed; and, Fig. 7, a perspective view of the blank with its flange.

Similar reference numerals refer to similar parts throughout the several views of the drawings.

The essential features of the latch are, a casing 4, a stem 3, a spring 8, and a pin 7. The casing 4 is a tube, preferably formed 40 from sheet metal, and provided with antipodal slots 5 extending at an angle of approximately 45 degrees relative to the axis of the casing, open at the front end, and provided with an internal flange 6 at the 45 rear end. This casing is formed preferably from a blank of sheet metal, shown in Figs. 6 and 7, in which the slots 5 are first punched out, and the blank then formed into a tube, thus forming a butted tube, as 50 shown in Fig. 5. The internal flange 6 may be bent first at right angles to the plane of the blank and then formed as the tube is formed, or the flange may be crowded in upon a suitably formed mandrel by a suitably formed die. The walls of slots 5 form

inclined planes after the manner of double screw threads. The stem 3 is preferably made of a straight piece of round stock of suitable diameter, provided with an annular groove 11 near its outer end, and having 55 its inner end bent at somewhat less than a right angle to form a swinging latch member 12. The stem 3 is provided with an aperture adapted to receive a pin 7. Pin 7 extends through the aperture in stem 3, and 60 its ends work in slots 5, bearing against the walls of the slots and thus imparting rotary motion to stem 3 when it is moved longitudinally. A collar 9 is provided adapted to fit snugly upon stem 3 and slidably in casing 4. The coil spring 9 fits into the casing and over stem 3. Flange 6 receives the inward thrust of spring 8 and collar 9 receives the outward thrust of the spring. Collar 9 is placed just within and against 70 pin 7, which prevents its being moved outward on stem 3 by the spring. Upon the outer end of stem 3 is mounted a cap 10, the inner edge of which is crimped into annular groove 11 to prevent its falling off. Cap 10 75 is loosely mounted upon stem 3 in order that when the cap is pressed by the thumb it may not rotate under the thumb but the stem may be free to rotate within the cap. Cap 10 and the outer end of stem 3 are surmounted 80 by a suitable handle or knob 2 which may be provided with an integral or attached escutcheon plate 13. The free end of latch member 12 may be somewhat flattened, as shown, in order to present a flat face to the 85 surface of door-casing 4.

The latch is assembled as follows:—The stem 3 is pushed through casing 4, spring 8 is placed over stem 3 and pushed into casing 4 till it rests against flange 6, collar 9 is 90 placed over stem 3 and pushed down upon spring 8 beyond the transverse perforation for pin 7. Pin 7 is then passed through slots 5 and stem 3, making a driving fit in the stem, and cap 10 is placed over the end of 100 stem 3 and its edge crimped into groove 11.

To apply the latch to a door, a hole, say of $\frac{3}{8}$ inch diameter, is bored through the door at a suitable point near its free edge, cap 10 is inserted from the inside of the 105 door, and the latch pushed through until the outer end of casing 4 enters the hole. The casing is made of a diameter slightly larger than the hole bored through the door, so that it makes a driving fit in the hole. The cas- 110

ing is driven in until flange 6 is flush with the inner surface of the door. Before driving, care should be taken that latch member 12 is so placed that it extends across the edge 5 of the door. On account of the driving fit no screws are necessary to secure the latch in the door. The knob 2 is then placed over cap 10 and the protruding stem, which guides the knob to its proper position, and 10 the knob may be fastened by means of screws or escutcheon pins to the front surface of the door. It will be appreciated that great care is not necessary in locating the hole into which the latch is to be driven, and there is 15 no strike or catch to be located on the door casing, so that the latch is very easily and quickly applied.

In use, to open the door, it is necessary simply to place the first and second fingers 20 under the flange of knob 2 and press with the thumb upon cap 10 so as to push stem 3 inward when latch member 12 will recede from the inner face of the door casing and swing around so that it will not engage the 25 door casing when the door is opened, as shown in Fig. 2. It will be understood that latch member 12 advances toward the inner surface of the door and the door casing at the same time that it swings around into the 30 locking position, and it will continue to swing around and advance until its free end engages the door casing. By this means the door will always be drawn up tight whatever may be the swollen or shrunken condition 35 of the wood, and all lost motion and rattle of the door is prevented.

Having thus described my invention so that any one skilled in the art pertaining thereto may make and use it, I claim—

40 1. A door latch comprising a casing adapted to be inserted in a round transverse hole in a door, said casing provided with a spiral slot, a stem mounted to reciprocate longitudinally in said casing, a pin through 45 said stem so arranged that it engages the walls of the spiral slot in said casing and rotary motion is imparted to said stem when it moves relative to said casing, a right-angular latch member on the inner end of said 50 stem, and a push element on the outer end of said stem.

55 2. A latch, comprising in combination, a

casing member, a longitudinally and rotary reciprocating stem member in said casing member, a swinging latch member on the 60 inner end of said stem member, a spring member within said casing member, and means for operatively connecting said casing member and said stem member in such a manner that when said stem member moves 65 longitudinally relative to said casing member rotary motion is imparted to said stem member.

3. A latch, comprising a cylindrical casing 4 provided with angular slots 5 in its 65 wall and an internal flange 6 at one end; a stem passing through said casing having a swinging latch member 3 on its inner end, a pin 7 passing diametrically therethrough and engaging the slots 5 by its ends; and a 70 spring 8 within said casing 4 confined between the internal flange 6 and the pin 7.

4. In a door latch, a cylindrical casing adapted to be driven into a round transverse hole in a door, a stem slidably mounted in 75 said casing, a spiral slot in said casing, means on said stem for engagement with the walls of the groove in said casing, a right-angular latch-member on the inner end of said stem adapted to swing into engagement with the 80 door-frame, and a push-cap mounted on the outer end of said stem, all so arranged that when said stem is pushed inward toward the door, said latch-member swings out of engagement with the door-frame both horizontally and vertically, and when released said latch-member swings toward and into engagement with the door-frame both horizontally and vertically. 85

5. A latch, comprising in combination, a 90 casing member, a longitudinally and rotary reciprocating stem member in said casing, a latch member integral with said stem member, a spring member within said casing member, and means for operatively connecting 95 said casing member, and said stem member in such a manner that when said stem member moves longitudinally relative to said casing member rotary motion is imparted to said stem member.

GEORGE WETTIG.
